REGULATING APPARATUS.

1,210,889.

Specification of Letters Patent. Patented Jan. 2, 1917.

Application filed November 18, 1911. Serial No. 660,945.

To all whom it may concern:

Be it known that I, JOSEPH BIJUR, a citizen of the United States, residing at New York, in the county of New York and State of New York, have invented certain new and useful Improvements in Regulating Apparatus, of which the following is a full, clear, and exact description, such as will enable others skilled in the art to which it appertains to make and use the same.

This invention relates to electrical systems, and with respect to its more specific features, to an electric system comprising regulators adapted to maintain a constant voltage therein.

One of the objects of the invention is to provide a device of the class described which shall rapidly respond in an accurate and sensitive manner to electrical changes in the system.

Another object is to provide a practical and efficient device of the class described which shall be simple and compact.

Another object is to provide reliable voltage-regulating apparatus in which sudden changes in the load may be made without disturbing the voltage thereon.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

The drawing, which represents one of various possible embodiments of the invention, is a diagrammatic plan.

It is believed that it will tend to a more complete appreciation of the various features of this invention to point out that in the illumination of railway cars in systems which comprise an axle-driven dynamo, the variation in voltage across the battery terminals that occurs as the speed of the car changes is relatively slow, since the cars do not speed up nor slow down instantly. There are, however, in addition to these slow changes, very rapid alterations caused by suddenly throwing on or off a large fraction of the total load comprising the lamps or other translating devices. These changes may occur in a very short interval of time,

usually in a fraction of a second, and with a slowly acting regulator, objectionable fluctuations in the voltage of the system would result.

The invention herein described is peculiarly adapted to eliminate these rapid fluctuations in voltage and provide as well a highly useful device which accomplishes many other desirable results that will be apparent from the following description.

Referring now to the drawing, 1 represents an axle-driven dynamo provided with a shunt field 2. The dynamo acts as a source of electrical energy for the distribution circuit, comprising the conductors 3 and 4. In the conductor 3 there is inserted an automatic switch. This comprises a solenoid 5, connected in series in the circuit, and a solenoid 6, connected in parallel between the mains 3 and 4, and having associated therewith a resistance coil 7 adapted to compensate for temperature changes. These solenoids are cumulatively wound and are adapted to coöperate with a core 8. The core 8 is operatively related to a switch arm 9 which is normally held, by means of a spring 10, in such position that the circuit through conductor 3 is broken. The action of a main switch of this type is well known.

Connected across the mains 3 and 4 is a storage-battery 11, and the several banks of lamps 12, 13, 14 and 15 are so arranged and connected as to be thrown across the mains in parallel with the battery by the substantially identical switches 16, hereinafter described in detail. Serially disposed in the conductors leading to these several lamp-circuits are rheostats 17, 18, 19 and 20, each of these rheostats comprising a series of resistance coils provided with contacts 21. These contacts are all arranged in substantially concentric form with respect to a shaft 22, on which is a spider 23, the arms of which, in this case, four in number, coact respectively with the several rheostats.

The circuit from the main 3 leads to the spider 23 and thence outwardly through the several arms to the corresponding rheostats and the several lamp-circuits constituting the load. It is to be noted in this connection that each lamp-circuit is provided with a separate resistance element, these resistances being all connected in parallel and being simultaneously and proportionately

varied in value as the spider 23 is rotated by the shaft 22. The rotary movement of shaft 22 is gained from the series motor, the armature of which is indicated at 24, and the shaft 25 of which is operatively connected with the spider by the worm and wheel mechanism 26. Mounted upon shaft 25 is a friction drum 27, having a spring-pressed brake-shoe 28 bearing thereon and serving to prevent the overrunning of the motor in either direction by inertia after the impelling power is withdrawn. This motor is serially connected in this embodiment and its field 29 comprises two equal and opposed windings normally neutralizing one another in effect. Leading from the point of connection of these windings is a conductor 30, which terminates at the pivot of a swinging contact 31, which is connected with the arms 32 and 33, the latter being provided with a retracting spring 34. Arm 32, and hence the contact 31, is controlled by the core 35 of a solenoid 36, connected in series with the low temperature co-efficient resistance 37 between the conductor 38 and the main 4.

The contact arm 31 is provided with a pair of spring contacts 39 and 40, respectively coacting with the fixed contacts 41 and 42. The latter contacts are respectively connected with the ends of the field winding of the controlling motor and are also cut into the main conductor 43, as shown, to provide a series field. In the action of this controlling or pilot motor, it will be seen that as contact 39 is swung into engagement with the contact 41, there will be provided a short-circuit through conductor 30 about the field winding 44, thus giving full effect to field winding 45 and causing rotation of the motor and swinging of the spider 23. On the other hand, if the contact 40 is swung into engagement with contact 42, the field winding 45 will be short-circuited, rendering the field winding 44 operative, and the motor will be driven in the reverse direction, thus reversing the movement of spider 23. It will thus be seen that when the contact arm 30 occupies mid-position, as indicated in full lines in the drawing, the motor will remain inoperative, but, upon it swinging in either one or the other direction, as due to an excess or deficiency in the field strength of voltage coil 36, then armature 24 will be rotated in such direction as to vary the several resistance elements 17, 18, 19 and 20 until the voltage is again brought to normal, whereupon arm 31 will again occupy mid-position. The spring contacts 39 and 40 are preferably employed in order that there may be given a slight rubbing action to the engaging surfaces as they are brought into operative relation to the stationary members 41 and 42.

Referring now in detail to the connections

of the several lamp-circuits, it may be noted that the several conductors 46 lead from the resistance elements 17, 18, 19 and 20 to the terminals 47 of the switches 16. These switches, all of which are substantially identical, are of the three-pole type, and the blades 48 and 49 respectively connect the terminal 47 with the conductor 50 at one side of the lamps and the main 4 with the conductor 51 upon the other side. Contact 52 is in each case permanently connected with a terminal 53, from which the blade 54 makes connection with the contact 55 of a conductor 56 upon the corresponding bank of lamps being thrown in circuit. Each conductor 56 is connected with the wire 38, and, hence, upon any bank of lamps being thrown on, there is a connection leading through spider 23 and one or more of the resistance elements and switches to conductor 38, and thence to the voltage coil 36 and the motor through conductor 57.

In the operation of this system, when one or more of the several lamp-circuits is thrown on by the switch 16, the voltage coil 36 is connected across the mains in parallel with the lamps. If, now, the voltage on the lamps, for any reason, tends to exceed a chosen normal value, the core 35 will be attracted to such an extent as to overcome spring 34 and make connection between the contacts 39 and 41. This will short-circuit the field winding 44, as above explained, and cause the armature 24 to rotate in such direction as simultaneously to increase the value of the several rheostats. This increase of resistance in series with the lamps will decrease the voltage impressed thereon, and the parts are so adjusted that when this voltage reaches the desired standard, the spring 34 will overcome the effect of the weakened field of coil 36 and again bring the contact 31 into its inoperative mid-position. The field windings 44 and 45 will then balance one another in effect and the impelling force upon shaft 25 will be withdrawn, causing the latter to stop instantly by the action of the friction brake 28. If, on the other hand, the voltage across the lamps becomes too low, there will arise an action which is the reverse of that above described, the field 45 being short-circuited, the pilot motor driven in the opposite direction, and the value of the several resistances decreased until a normal condition has been attained. If the entire lamp load is thrown off, the circuit through voltage coil 36 and through the armature of the motor, the latter comprising conductor 57, running from conductor 38, is broken and there is thus avoided any leakage of current when the system is not in use. Upon one or more of the banks of lamps being thrown into or out of circuit, its corresponding rheostat is also cut out, and hence there is no appre-

ciable effect upon the voltage of the remaining lamp-circuits. For example, if the lamp-circuit 12 is disconnected, the circuit through resistance element 17 is opened, but 5 the several resistance elements 18, 19 and 20 remain in circuit to control the voltage upon the lamp-circuits 13, 14 and 15. In like manner, if a bank of lamps, as 13, be thrown on, the corresponding resistance element 18 is simultaneously cut in. The 10 advantage of this action will be rendered obvious by contrast with that obtaining in a system in which a single variable resistance governs the voltage upon several lamp-circuits. In the latter case, the entire load 15 passes through this resistance and the voltage drop in this rheostat, which is, of course, equal to the product of its ohmic resistance, and the current passing therethrough will 20 vary with the latter fact. If, now, a section of the load be thrown off or on, there will be a corresponding variation in the current passing through the rheostat, a proportional variation in the voltage drop in the 25 rheostat, and a consequent change in the voltage impressed upon the lamps still in circuit. This change would be instantaneous and would result in a sudden excess or deficiency of the lamps which were still on. 30 In the present case, however, any bank of lamps may be thrown on or off and there is no variation in the current passing through the voltage-controlling rheostats of the remaining circuits.

35 It will accordingly be seen that there is provided apparatus in which the several objects of this invention are achieved.

As many changes could be made in the above construction and many apparently 40 widely different embodiments of this invention could be made without departing from the scope thereof, it is intended that all matter contained in the above description or shown in the accompanying drawing shall 45 be interpreted as illustrative and not in a limiting sense. It is also to be understood that the language used in the following claims is intended to cover all of the generic and specific features of the invention herein 50 described and all statements of the scope of

the invention, which, as a matter of language, might be said to fall therebetween.

Having described my invention, what I claim as new and desire to secure by Letters Patent is:

1. In apparatus of the class described, in combination, a source of current, a plurality of lamp circuits, means adapted separately to connect said lamp circuits to said source of current, a plurality of variable resistance media, one of which is serially connected in each lamp circuit, a motor, a voltage relay controlling said motor and connected to present a field proportional to the voltage across the lamps, and means varying said media actuated from said motor to maintain the voltage across the lamps substantially constant, said relay and motor being connected with a lamp circuit on the lamp side of said first connecting means. 60

2. In apparatus of the class described, in combination, a source of power, a plurality of lighting circuits each comprising a pair of conductors in one of which is serially connected a resistance medium and a bank of lamps bridged in parallel across said conductors, a plurality of double-pole switches respectively adapted to connect said circuits across said source in parallel one with another, each of said resistance media being so disposed in the corresponding conductor as to be traversed by the entire current passing to the corresponding bank of lamps, said several resistance media each comprising a plurality of contacts grouped 85 about a rotary member, a member mounted upon said rotary member and provided with arms respectively coacting with said sets of contacts, an electric motor controlling said rotary member, and means controlled in accordance with the voltage across said lamps and controlling the direction and duration of drive of said motor. 90

In testimony whereof I affix my signature, in the presence of two witnesses.

JOSEPH BIJUR.
